UNITED STATES PATENT OFFICE.

LYMAN H. LOOMER, ANDREW F. LOOMER, AND LOWELL M. SMITH, OF BIRMINGHAM, CONNECTICUT, ASSIGNEES TO L. L. LOOMER & SONS, OF SAME PLACE.

IMPROVEMENT IN CORSETS.

Specification forming part of Letters Patent No. **145,665**, dated December 16, 1873; application filed September 24, 1873.

To all whom it may concern:

Be it known that we, LYMAN H. LOOMER, ANDREW F. LOOMER, and LOWELL M. SMITH, of Birmingham, in the county of New Haven and State of Connecticut, have invented a new Improvement in Corsets; and we do hereby declare the following, when taken in connection with the accompanying drawing and the letters of reference marked thereon, to be a full, clear, and exact description of the same, and which said drawing constitutes part of this specification, and represents, in—

Figure 1, a diagram of the several parts from which each half of the corset is formed; Fig. 2, one-half of a corset as made from the several parts.

This invention relates to an improvement in method of cutting corsets, whereby the employment of gores or pieces less than the length of the corset is unnecessary; and it consists in a corset made from several parts cut in the form shown in the accompanying drawing, and hereinafter described.

The front 1, Fig. 1, is, preferably, cut of sufficient width to form the pocket for the steel, gradually swelling toward the upper end upon the opposite edge. The second piece 2 is substantially alike upon both edges, swelling from about half-way its length toward the top. The third piece 3 has its edge toward the front corresponding to one edge of the second piece, so that when the three pieces 1 2 3 are joined together, the requisite fullness will be given to the top without the introduction of gores. These three parts downward from where the fullness commences are of nearly equal width, the edges of each piece through that portion being nearly parallel to each other. The third piece upon the rear edge curves outward to-

ward the top. The fourth or hip piece is curved upon its front edge, corresponding to the rear edge of the third piece, the opposite edge curved outward rapidly toward the bottom, to commence the curvature at the hip. The front edge of the fifth piece corresponds to the rear edge of the fourth piece, and the rear edge of the fifth piece is curved substantially as the front edge, the fourth and fifth pieces forming the fullness necessary for the hip. The sixth or back piece is straight upon its rear edge, and curved its entire length, and, when attached to the rear edge of the fifth piece, gives the requisite curvature for the back. The broken lines on the several pieces indicate the pockets for the bones.

The parts thus cut are united at their respective edges in the usual manner, and form one-half of the corset, as seen in Fig. 2; the other half is the same, except the parts are cut the reverse.

By this method of cutting the most perfect form is given to the corset, and without the employment of gores or pieces shorter than the length of the corset.

We do not wish to be understood as broadly claiming a corset made without gores; but

We claim as our invention—

The herein-described corset, made from pieces having the configuration herein described, and shown in accompanying illustration.
